(57) CLAIM

The ornamental design for a heater unit, as shown and described.

DESCRIPTION

In a preferred embodiment the nature of this product is as a heater that heats personal care fluids such as shaving cream, lotion or the like, and then dispenses them.

FIG. 1 is a left, top, frontal perspective view of a heater unit embodying our new design;

FIG. 2 is a left side elevational view thereof, the right side elevational view being a mirror image thereof;

FIG. 3 is a front elevational view thereof;

FIG. 4 is a rear elevational view thereof;

FIG. 5 is a top plan view thereof;

FIG. 6 is a bottom plan view thereof;

FIG. 7 is a left, top, frontal perspective view of a second embodiment;

FIG. 8 is a left side elevational view thereof, the right side elevational view being a mirror image thereof;

FIG. 9 is a front elevational view thereof;

FIG. 10 is a rear elevational view thereof;

FIG. 11 is a top plan view thereof; and,

FIG. 12 is a bottom plan view thereof.

The broken line representations along the side walls of the first embodiment in certain views are for purposes of illustration only and form no part of the claimed design.
